TRACKWAY SYSTEM FOR TRAIN CONTROL

Max Theodore Wintsch, Lancaster, Pa., assignor
of fifty-one per cent to Newton M. Weaver,
Lancaster, Pa.

Application September 3, 1941, Serial No. 409,335

15 Claims. (Cl. 246—63)

This invention relates to a trackway system adapted particularly for use where the traffic is light rolling stock, such as subway trains and suburban cars, and where there are relatively short block sections. By this invention high speed operation of such traffic will be entirely safe and feasible.

One of the objects of my invention is to provide a trackway system which will supply control current for a four indication cab signal, utilizing the track rails and an auxiliary trackway conductor circuit to convey the control current.

Another object of my invention is to provide a system in which the block sections may be divided into so-called main and intermediate block sections and control current may be independently flowed in the track rails and auxiliary trackway conductor circuits of each or they may be interlocked as desired to indicate varying traffic conditions.

This invention is also concerned with the provision of adequate safeguards to insure that any failure of the equipment will result in the effecting of a restrictive condition indication in the cab signal, insuring against accident.

According to this invention, the track rails are divided into block sections, each of which includes a main block section and, at the exit end of each block section, an intermediate block section. Electrical circuits are provided for impressing control current upon the track rails in the main and intermediate block sections in accordance with traffic conditions in advance block sections. An auxiliary current conductor is provided in the intermediate block sections and extends into or through the main block sections. Electrical circuits are provided for the energization of the conductors and these circuits are likewise controlled by advance traffic conditions, the intermediate and main block auxiliary trackway conductor circuits being independently controlled. Preferably, a single pick-up transformer is provided on the vehicle to be controlled and this is effective for receiving the current in the rails and in the auxiliary trackway conductor circuits and suitable signalling and controlling equipment is provided to translate the current received by the pick-up transformer from the rails and the auxiliary trackway conductor circuits into signals and/or controls.

In order that my invention may be easily understood, I will describe the same in conjunction with the attached drawings, in which,

Figure 1 is a schematic layout of the track and auxiliary trackway conductor control circuits,

Figure 2 is a diagram illustrating the flow of control current in the track rails and auxiliary trackway conductor circuits and shows the signal indications effected when a vehicle occupies an advance main block section,

Figure 3 is a similar view showing a vehicle in an advance intermediate block section,

Figure 4 shows a still further traffic condition with vehicles in both main and intermediate block sections, and

Figure 5 is a schematic layout of a typical cab signal and control arrangement which may be operated by the track system shown in Figure 1.

15 THE TRACK CIRCUITS

Referring to Figure 1, the track rails are divided into a plurality of main or primary block sections, main sections A and B being shown. At the exit end of each main block section, an intermediate block section is provided. In the drawings, intermediate block sections B' and C' are shown. The exit end of block A, which is not shown, would include a similar intermediate block section. The rails in each section A, B', B and C' are insulated from the rails in the next adjacent section, the insulation 2 being diagrammatically shown in the drawings. Each block section, therefore, constitutes an electrically insulated current-conducting portion of trackage for the reception of train control current.

In describing the track circuit arrangement, reference will be made primarily to main block section A, which is occupied by a vehicle V, main block section B, and intermediate block section B'. Each main and intermediate block section will be similarly equipped and, accordingly, corresponding numbers have been applied to the minor portion of the track and control relays for block section B, shown in Figure 1, for convenient understanding of the invention.

Each main and intermediate block section is provided with a high voltage transformer 3, supplied with current from a transmission line 4 to which the primary 5 of the transformer 3 is permanently connected. Each main block section is provided with a track transformer 6 and each intermediate block section with a similar track transformer 7. The primaries 8 and 9, respectively, of said track transformers, one side of each of which is permanently connected to secondary 10 of the high voltage transformer 3, are fed with current from the secondary 10 only when predetermined track conditions exist, as will be more fully hereinafter described. The secondaries 11 and 12 of the track transformers 6 and

1 are permanently connected to the track rails in the main and intermediate block sections, respectively. In each main block section, the secondary 11 is connected through leads 13 and 14 and in each intermediate block section the secondary 12 is connected across the track rails by leads 15 and 16. In other words, the primaries of the track transformers are controlled to effect the supply of current to the track rails, the secondaries being permanently connected to the track rails.

Each main block section is provided with a track relay TR (a letter corresponding to the block section letter has been added to each relay in the track circuit). Likewise, each main block section is provided with a control relay CR. The intermediate block sections are provided with track check relays TIR and safety relays SR.

The track relays TR are effective for controlling the supply of signalling or control current to the track rails in the next rearward adjacent intermediate block sections. The control relays CR are similarly effective for controlling the supply of such current to the track rails in the next rearward main block sections. This will be apparent from an examination of Figure 1 where track relay TRA, through its armature 17, when energized and elevated into engagement with front point of contact 17' (it is shown in deenergized and lowered position), connects the controlled side of the primary 9 of track transformer 1 for intermediate block section B', with the secondary 10 of high voltage transformer 3, through leads 18, 19, and 20. In the same manner, control relay CRA, through its armature 21, connects the primary 8 of track transformer 6 in circuit with the secondary 10 of high voltage transformer 3, through leads 18 and 22, armature 23 of relay TRA, front point of contact 24, lead 25, armature 26 of track check relay TIRB, front point of contact 27 and leads 28 and 29.

By this means, the supply of control current to the track rails of each of the main and intermediate block sections is electrically controlled in accordance with existing traffic conditions.

Extending throughout each intermediate block section and into the exit end at least of each main block section is an additional means for supplying control current. This is in the form of an auxiliary trackway conductor circuit including a conductor bar 30, having sections a and b, connected together by a choke coil 31. The length of the bar 30b in each main block section will depend upon the type of rolling stock normally using the trackage and its normal operating speed, as well as the length of the main block sections. In many instances, if the bar extends one thousand feet into the main block section, it will provide adequate warning of conditions in the intermediate block sections to permit safe operation, even under abnormal weather and other conditions. It is desirable, however, to extend the bars throughout substantially the entire length of the block sections or, if less than the entire length, to provide adequate right-of-way signals to indicate the exact track conditions. The bars 30 are preferably of insulated copper or other current conducting wire and are spliced or otherwise secured, insulated against ground, to the cross ties. Each bar, when electrically connected, constitutes a loop upon which current may be impressed.

Each intermediate block section has a motor alternator set 32 or other similar device for sup-

plying control current to the trackway conductor circuit. This set includes a motor 33 and an alternator 34 adapted to supply alternating current of say 100 cycles at 30 volts when the motor is in operation. The trackway conductor section 30b is normally connected to the alternator 34 by leads 35, 36, and 37, so that when the motor alternator set 32 is in operation, current of 100 cycles frequency flows through the trackway conductor section 30b. The trackway conductor section 30a is controlled by the track relay in the next advance main block section as will be hereinafter described. Unlike section 30b it is not permanently connected to the alternator to be energized whenever the alternator is in operation, but only when the traffic conditions in the next advance block are such that the application of control current thereto is proper.

Operation of the motor alternator set 32 is controlled by track relay TR of the next advance block section. A source S of low voltage current, say 60 cycles at 120 volts, extending along the right-of-way, provides current for the motors of the respective motor alternator sets, one side of each motor being normally connected to the line through a lead 38. The other side of the source S connects by lead 39 with armature 40 of track relay TR and a lead 41 connects to the other side of the motor 33, the circuit being complete when armature 40 falls into engagement with contact point 42 to which lead 41 is connected.

Relay CR is a direct current relay and is utilized as a control, being rendered inoperative in the event of any failure of the auxiliary trackway conductor circuit. This is effected in the following manner: A battery 43, or a rectifier if preferred, is connected to one side of the relay CR through lead 44. A lead 45 from the other side of the battery connects with lead 36 joining with the bar 30a. Choke coil 31 which will pass direct current connects bars 30a and 30b. Lead 35 from the conductor 30b connects with leads 46 and 47 extending to a choke coil 48 which blocks the alternating current and connects by a lead 49 to the relay CR. A blocking condenser BC is provided in lead 35 of the auxiliary trackway conductor circuit to prevent the passage of direct current from the battery 43 of the control relay circuit into the circuit of the alternator 32, while at the same time permitting the free passage of alternating current to the auxiliary trackway conductor circuit. The circuit traces from battery 43 through leads 45 and 36, bar section 30a, choke coil 31, bar section 30b, leads 35, 46 and 47, choke coil 48, and lead 49 to the relay CR. If there be any break in the auxiliary trackway conductor circuit, therefore, relay CR will be deenergized and its armature 21 will fall, interrupting the circuit for the supply of control current to the track rails in the next rearward main and intermediate block sections, effective to initiate a suitable signal or control or both.

To insure that the battery will always be fully charged, a trickle charger 50 may be provided which is supplied with current from the source S.

Track check relay TIR is also effective for controlling the supply of signalling or control current to the track rails in the next adjacent rearward main block section. Thus, when track relay TRA is deenergized (as shown in Figure 1) and armature 23 is away from front point of contact 24 which normally completes the circuit for the control current in the rails of main block section B, armature 23 falls into engagement with back

point of contact 51 and current from the secondary 10 of high voltage transformer 3 flows through lead 18, armature 21, lead 22, armature 23, back point of contact 51 of relay TRA, a lead 52 to armature 53 of track check relay TIRB, a point of contact 54, lead 55, a point of contact 56 which is engaged by armature 57 of safety relay SRB and a lead 58 which connects with lead 29 to the primary 8 of track transformer 6 for block section B.

By this arrangement, current is fed to the track rails in the next rearward main block section (main block section B, for example) when a vehicle occupies the next advance block section (main block section A as shown in Figure 1).

Track check relay TIR, like track relay TR, is controlled by conditions existing in the intermediate block section across the rails of which it is electrically connected, although it is also controlled by relay TRA as will be brought out.

Safety relay SR is provided in each intermediate block section so that, in the event of failure of the alternator 32 for any reason, the supply of the control current for the next rearward main block section will be interrupted. Referring to Figure 1, the safety relay SRB is shown in energized position, it being connected by leads 59 and 60 across the leads 36 and 46 from the alternator 34. The alternator in Figure 1 is in operation because track relay TRA is open and armature 40 is in engagement with point of contact 42 closing the circuit for the motor 33 of the motor alternator set 32, through lead 41. The armature 40 is normally connected to one side of the source of low voltage current S through lead 39. The other side of the motor is connected permanently to the current source S through lead 38. Armature 57 of relay SRB is thus elevated into engagement with point of contact 56, closing the circuit for the supply of current to the track rails of main block section B through control of primary 8 of track transformer 6. The circuit is from secondary 10 of high voltage transformer 3, through lead 18, point of contact 61, armature 21, lead 22 to armature 23 of relay TRA, point of contact 51, lead 52, armature 53 of track check relay TIRB, point of contact 54, lead 55, point of contact 56, and armature 57 of safety relay SRB and leads 58 and 29 to one side of the primary 8. The other side of the primary 8 is normally connected to the secondary 10 of the high voltage transformer 3 by lead 62.

Thus, when a vehicle occupies an advance main block section control current for the track rails in the next rearward main block will flow therein so long as the alternator remains in operation. Should the alternator fail for any reason or should the current supply for track check relay TIR fail because of a broken rail or an obstruction in the intermediate block section to which it is connected, safety relay SR will be deenergized and control current in the corresponding main block will fail, resulting in the establishment of a warning signal in any vehicle occupying or entering the main block, as will be hereinafter described.

Armature 17 of track relay TRA is provided with a back point of contact 63 which is effective for controlling the flow of current to track check relay TIRB in the event of deenergization of track relay TRA. The circuit is from the secondary 10 of high voltage transformer 3 through leads 18 and 19, armature 17, back point of contact 63, a resistor 64 effective for reducing the current to that sufficient for operation of track check relay TIRB, and lead 65 to the relay TIRB. The other

side of the secondary 10 is normally connected to the other side of relay TIRB through leads 62, 66 and 15 to the track rail to which relay TIRB is connected by lead 67. Thus, when relay TRA is deenergized relay TIRB will remain energized unless the current supply through the rails of the intermediate block section is shunted out, for example, by a vehicle occupying intermediate block section B'.

10 Track relay TRA is provided with a fourth armature 68 which is effective when relay TRA is deenergized for completing the circuit for the intermediate section 30a of the auxiliary trackway conductor circuit. The circuit is from alter-

15 nator 34, through blocking condenser BC, leads 35, 46 and 69 to armature 68, point of contact 70 and lead 71 to one side of the trackway conductor section 30a. The other side of the conductor 30a is normally connected to the other side of the alternator through lead 36.

20 Track check relay TIRB is provided with a third armature 72 which is effective for energizing the motor alternator 32 when relay TRA, which normally controls it upon deenergization, is energized and relay TIRB is deenergized by reason of a vehicle in intermediate section B', for example. Under such conditions, armature 72 falls into engagement with point of contact 73 and current is then fed from source S through lead 74, armature 72, point of contact 73, and a lead 75 to one side of motor 33 of the motor alternator 32. The other side of the motor is normally connected to the source 37 by lead 38. By this arrangement control current is fed to trackway conductor section 30b when a vehicle occupies the intermediate block section.

25 Assuming now that a vehicle V is operating in block section A and moving in the direction of the arrow, the supply of current for track trans-

30 former 7 will be interrupted in the following manner: The vehicle V will shunt out the current supply for the track relay TRA which is connected across the rails of main block section A, in which the vehicle V is operating. Armature 17 (as well as all the armatures) will thereupon fall and the current supply for the primary 9 of track transformer 7, which is fed from the secondary 10 of the high voltage transformer 3 through leads 18 and 19, armature 17, and point of contact 17', connected with lead 20 from the primary 9 of track transformer 7, will be open.

35 Thus, no current will be flowing in track transformer 7 which supplies control current for intermediate block section B' and the rails in intermediate block section B' will not be energized when a vehicle occupies block A.

40 Armature 17 will, however, fall into engagement with point of contact 63 and current will thereupon be fed to the track check relay TIRB through the circuit from secondary 10, through leads 18 and 19, armature 17, point of contact 63, resistor 64 and lead 65 to relay TIRB. The other side of this relay is normally connected to the other side of the secondary 10 through a lead 67 to one of the track rails and from the track rail by leads 15 and 66.

45 Thus, relay TIRB will be energized even though no current is flowing in winding 12 of transformer 7 which supplies current to the rails to which relay TIRB is connected, but current will be supplied to relay TIRB from secondary 10 only when the track relay in the next advance block is deenergized. In the event a vehicle occupies an intermediate block section, it of course shunts not only the supply current for the track

check relay but also the resistor circuit as well. While the vehicle occupies block A and track relay TRA is deenergized, armature 40 connected with lead 39 from the source of low voltage current 37, will be in contact with point of contact 42 which connects through lead 41 to motor 33 of the motor alternator set 32. The motor 33 will, therefore, be in continuous operation and alternating current 100 cycles per second will be fed into the trackway conductor sections 30a and 30b. This is effected in conductor 30a through blocking condenser BC, leads 35, 46 and 69, armature 68 of relay TRA, point of contact 70 and lead 71. The other side of trackway conductor section 30a is normally connected to the alternator 34 by lead 36. Trackway conductor section 30b is normally connected to the alternator 34 so that when the alternator is in operation current of 100 cycles frequency is fed to the trackway conductor section 30b. This circuit is through blocking condenser BC, and lead 35, trackway conductor section 30b, lead 37 and lead 36 to the other side of the alternator.

Thus, when a vehicle occupies block A, current of 100 cycles per second frequency will be impressed upon the trackway conductor sections 30a and 30b of intermediate block section B'.

The rails of main block section B will be supplied with current from track transformer 6 (this may be alternating current of 140 cycles at 30 volts). This is effected by lead 62 from one side of the secondary 10 of high voltage transformer 3 to one side of the primary 8 of track transformer 6. The other side of the secondary is connected to the primary 8 through lead 18, point of contact 61 of armature 21 of control relay CRA, lead 22, armature 23 of track relay TRA, back point of contact 51, lead 52, armature 53 of track check relay TIRB, contact 54, lead 55, point of contact 56, and armature 57 of safety relay SRB, and leads 58 and 29.

Thus, the track rails in main block section B will be energized with alternating current of 140 cycles when a vehicle occupies block A.

Since track control current will be flowing in main block section B when block A is occupied, as previously described, track relay TRB will be energized and track control current will be supplied to intermediate block section C'. No current will be flowing in the auxiliary trackway conductor circuit of intermediate block section C', however, since track relay TRB is effective for energizing the circuit for the motor alternator set for that block section only when relay TRB is deenergized. Also, track control current will be supplied to main block section C since armature 17 of track relay TRB which corresponds to relay TRA will be in engagement with a point of contact 17', closing the circuit for the primary 8 of the track transformer 6 which supplies current to the rails of main block section C (not shown) in the same manner as TRA when it is energized.

Similarly, no current will be flowing in the trackway conductor section of main block section C since the check relay TIR for that block will be energized by the control current supplied from its track transformer.

Thus, when a vehicle occupies block A, block sections C and C' will have current of 140 cycles per second frequency impressed upon their track rails and no current will be flowing in their respective trackway conductor sections.

Recapitulating the conditions existing in the

track and loop circuits as described above, and referring to Figure 2, the following will be the current flowing in the various circuits, with main block section A occupied: (The portions shown in full lines represent track rails or trackway conductor sections which are energized and the dotted line portions are deenergized or have no control or signalling current impressed thereon.)

10

Main block section A

- (a) Current shunted by vehicle V causing de-energization of the track relay TRA
- (b) No current in the auxiliary trackway conductor circuit

15

Intermediate block section B'

- (a) No current in the track rails. Nevertheless, relay TIRB remains energized by current from winding 10, through register 64

20

- (b) Current of 100 cycles frequency in the auxiliary trackway conductor circuit

25

Main block section B

- (a) Current of 140 cycles frequency in the track rails

25

- (b) Current of 100 cycles frequency in the auxiliary trackway conductor circuit

Intermediate block section C' and main block section C

- (a) Current of 140 cycles frequency in the track rails

- (b) No current in the auxiliary trackway conductor circuit.

Now assume that the vehicle occupies intermediate block section B', as shown in Figure 3, instead of main block section A and also bearing in mind the showing of Figure 1. This vehicle will shunt out winding 12 supplying current for track check relay TIRB, causing armature 26 which controls the supply of current to track transformer 6 to fall and no control current will flow in the track rails of main block section B. Armature 72 of relay TIRB will fall into engagement with point of contact 73, completing the circuit for the motor alternator 32 which will thereupon supply current to the trackway conductor section 30b of main block section B. Since there is no control current in the rails of main block section B, relay TRB will fall and the alternator for intermediate block section C' will be set in operation, supplying current to the loop circuit. Since there is no vehicle in main block section A, track relay TRA which controls the energization of the auxiliary trackway conductor circuit for intermediate block section B' through armature 70 will be energized and the circuit for the trackway conductor of intermediate block section B' will be open and no current will flow therein.

Under such conditions—a vehicle occupying intermediate block section B' and no vehicle in main block section A, the control and signalling current in the track and auxiliary trackway conductor circuits will be as follows:

- (a) Current shunted by vehicle V causing de-energization of check relay TIRB

- (b) No current in the auxiliary trackway conductor circuit

Main block section B

- (a) No current in the track rails

- (b) Current of 100 cycles frequency in the auxiliary trackway conductor circuit

Intermediate block section C'

- (a) Current of 140 cycles frequency in the track rails
- (b) Current of 100 cycles frequency in the auxiliary trackway conductor circuit.

Referring now to Figure 4 where a vehicle V occupies main block section A and another vehicle X is following in overlap block section B', the conditions are as follows: Vehicle V shunts out relay TRA; armature 40 completes the circuit for motor alternator 32 and armature 68 completes the circuit for the loop circuit in overlap block section B'. Vehicle X shunts out relay TIRB and armature 26 which controls the supply of current for track transformer 6 will be open—no current will be impressed on the track rails of main block section B. Relay TRB will thereupon open, its armature 17 falling into engagement with point of contact 63 completing the circuit for the track check relay for intermediate block section C' (in the same manner as previously described in connection with Figure 2 where relay TRA is open). Armature 72 of relay TRB will complete the circuit for the alternator for overlap block section C' and current will flow in the auxiliary trackway conductor circuit for overlap block section C'.

The track and auxiliary trackway conductor circuit conditions will be:

Main block section A

- (a) Current shunted by vehicle V causing de-energization of track relay TRA
- (b) No current in the auxiliary trackway conductor circuit

Intermediate block section B'

- (a) Current shunted by vehicle X causing de-energization of track relay TIRB, normally supplied by current from winding 10 when the track relay in the advance main block section is de-energized
- (b) Current of 100 cycles frequency in the auxiliary trackway conductor circuit

Main block section B

- (a) No current in the track rails
- (b) Current of 100 cycles frequency in the auxiliary trackway conductor circuit

Intermediate block section C'

- (a) Current of 140 cycles frequency in the track rails
- (b) Current of 100 cycles frequency in the auxiliary trackway conductor circuit.

THE CAB CIRCUITS

The cab signal arrangement shown in Figure 5 will now be considered.

Suspended on the vehicle a distance ahead of the first pair of wheels above the rails and on the side adjacent the bar 30 (Figure 5), there is provided a pick-up transformer 150 which is adapted to receive by induction the current impressed upon the rails or upon the loop 30. The current so induced is fed to an amplifier 151 and from there to a pair of vibrating reed relays 152 and 153. The relays are tuned by condensers 154 and 155 respectively so as to vigorously vibrate when current is induced in the pick-up transformer 150 and passes through the amplifier to the relays 152 and 153; the relay 152 being responsive to alternating current of a frequency of 140 cycles per second corresponding to the cur-

rent impressed upon the track rails and the relay 153 being responsive to alternating current of 100 cycles per second corresponding to the current impressed upon the various loop circuits.

5 (These reed relays are well known and are more particularly described in my United States Patent No. 2,105,134.) Current from a battery source 156 is fed to a vacuum tube amplifier 151 and, when either of the relays 152 or 153 is in vibration, current is fed to control relays.

Referring to the recapitulation of conditions existing in the track and loop circuits with main block section A occupied by a vehicle and referring to Figure 2, it will be observed that intermediate

15 block section C' has current of 140 cycles frequency impressed upon the track rails but no current in the auxiliary trackway conductor circuit. Relay 152 is responsive to alternating current of a frequency 140 cycles per second and is, therefore, in vibration when a vehicle enters overlap

20 block section C' with main block section A occupied. Grid 158 of vacuum tube 157 is thereby influenced resulting in a flow of current through the tube's plate-cathode circuit 159, energizing control relay 160. Relay 160 is connected to battery 156 by leads 161 and 162. The other side of relay 160 is connected to the plate-cathode circuit 159 by lead 163.

25 When relay 160 is energized, its armatures will all be elevated as shown in Figure 5. Its armature 164 will engage front point of contact 165 carrying current from the battery 156 through leads 162, 161, 166 and 167 to signal light 168 which may be colored green. The other side of

30 the signal light 168 is connected directly to the battery 156 through ground connection by lead 169. Armature 170 will engage front point of contact 171 and will complete a circuit from the battery 156 through leads 162, 161, 166 and 172

35 to back point of contact 173 of signal relay 174, through armature 175 of signal relay 174 and lead 176 to a solenoid valve 177, the other side of which is connected to the power source 156 through ground by lead 178. The solenoid valve 177 is thus normally energized and is effective for closing the air supply line to the alarm whistle 179.

40 If the train be electrically operated, a holding coil 180 may be provided effective for holding the circuit breaker for the main power supply in closed position. If this be employed, armature 181 will be supplied on signal relay 160 and this will close the front point of contact 182 connected by lead 183 to one side of the holding coil 180 thus supplying current to the holding coil 180 from the battery 156 through the leads 162, 161 and 166. The other side of the holding coil is connected to the power supply 156 through ground connection.

45 Thus, the operator will get a green or clear signal indication as his vehicle moves through intermediate block section C'. When the vehicle moves into the zone of the loop circuit of main block section B, however, current of 100 cycles frequency is flowing in the auxiliary trackway conductor circuit as well as the 140 cycle current in the track rails. The current in the loop circuit will be picked up inductively by the pick-up transformer 150 and after passing through the amplifier will energize reed relay 153 which is tuned to 100 cycles per second. When reed relay 153 is in vibration, current will be fed to grid 184 in the radio tube resulting in

50 a flow of current through the tube's plate-cathode

circuit 185, energizing control relay 174. Thus, current will flow from the power source 156 through leads 162, 161, 166, and 186, front point of contact 187, armature 188 and lead 189 to a signal light 190 which may be colored yellow. The other side of the signal light 190 is connected to the power source 156 through ground connection by lead 169.

Since 140 cycle current is also flowing in the rails of main block section B, reed relay 152 will also be in vibration and the green signal light will be illuminated so long as the vehicle continues to move through main block section B.

Thus, with block A occupied, a train moving through main block section B will get a clear indication (green), if the loop circuit does not extend throughout the extent of main block section B, until it reaches the zone controlled by the auxiliary trackway conductor circuit whereupon it will get an approach medium signal (green over yellow) indicating to the operator that he should approach at medium speed.

When the vehicle passes from main block section B into intermediate block section B' the green signal light will be extinguished since the track rails in that section are not energized and an approach signal (yellow over red) will be given in the following manner: Since current of 100 cycles per second is still flowing in the auxiliary trackway conductor circuit of intermediate block section B', the yellow light will remain illuminated, current being supplied in the manner just described for main block section B. There is no control current in the track rails of intermediate block section B', however, and relay 152 will not be energized. As a consequence, control relay 160 will be deenergized and its armature 164 will fall, completing the circuit for a signal light which may be colored red. The connection is from armature 164, back point of contact 191 and lead 192 to the signal light 193, the other side of which is connected to the power source 156 through ground connection by lead 169.

The supply of current for the solenoid valve 177 will likewise be interrupted since armature 175 will be elevated away from the back point of contact 173 breaking the circuit from the power source 156. Likewise the holding coil 180 will be deenergized by reason of the dropping of armature 181 away from front point of contact 182 which connects the holding coil to the power source 156. A reset button 194 may be provided which is effective for connecting the holding coil 180 and the solenoid valve 177 with the power source 156 when the button 194 is brought into engagement with the contacts 195 and 196 completing the circuit from the power source 156 through leads 162 and 197 to contact 195, through button 194 to contact 196, and through lead 198 to the holding coil, and lead 199 (shown in dotted lines, since it may be optional) to the solenoid valve 177. The yellow and red signals will continue to be illuminated so long as the vehicle rails in intermediate block section B' are not energized, even though the reset button be held in engagement.

When the vehicle enters block section A which is already occupied by the vehicle V, there will be no current flowing in the rails for it has been shunted out by the vehicle V. Thus neither relays 152 and 153 will be in vibration and both relays 160 and 174 will be deenergized. This will bring armature 164 into engagement with back point of contact 191 and the danger signal will be il-

luminated. Armature 188 will move away from front point of contact 187 interrupting the supply of current for the caution signal light 190 and armature 170 will drop from front point of contact 171 breaking the current supply circuit for solenoid valve 177 and the whistle 179 will be sounded. The supply of air for the braking system of the vehicle may be exhausted through the whistle 179 and thus the vehicle brakes will be applied upon deenergization of the solenoid valve 177.

Armature 181 will drop away from front point of contact 182 thus interrupting the supply of current for the holding coil 180 and the main circuit for the supply of current to the driving motors, if the engine be electrically driven, will be interrupted.

Should the operator desire to continue movement of the vehicle, he may manually operate the reset button 194, thus energizing the holding coil 180 and the valve 177. The danger signal will continue to be illuminated, however, so long as the vehicle carrying the signalling equipment is occupying the same block as another vehicle or the supply of current to the track rails is interrupted for any other reason.

The cab signals appearing in a vehicle approaching occupied main block section A would be:

- 30 Intermediate block section C': Green—clear—proceed at full speed
 Main block section B: Green over yellow—approach medium—approach next signal or indication point at not exceeding medium speed
 35 Intermediate block section B': Yellow over red—approach—prepare to stop at next signal or indication point. Reduce to low speed.
 Main block section A: Red—danger—stop at once.

40 The cab signals which would be given for the other conditions are shown in Figures 3 and 4 where the cab signal designations have been shown over the various block sections.

45 Assuming that all blocks are unoccupied, relay TRB will be energized since it is only de-energized when the supply of current is shunted out by a vehicle in block B or when the current is shunted out of the track rails in intermediate block section B' causing relay TIRB to fall and interrupting the supply of track relay current to main block section B at point of contact 21. When relay TRB is energized no current flows in the auxiliary trackway conductor circuit for 50 intermediate block section C' since the supply of current to that circuit is controlled by armature 72 of relay TIRB which is elevated away from its back point of contact 73 and by armature 40 of relay TRA which is elevated from its back point of contact 42. There is, therefore, train cab control current flowing in the track rails of all block sections and no train cab control current flowing in the trackway conductors. Thus 55 a vehicle moving along the trackway would continuously exhibit a green or clear-proceed at full speed signal.

Should there be any failure of any auxiliary trackway conductor circuit, control relays CR will be deenergized. They are direct current relays receiving current through the auxiliary trackway conductor circuits in the manner previously described. When any control relay CR is deenergized, the circuit for the track current in the next rearward main block section will be 60 opened and since no current will then be flowing

in the rails, the red signal will be lighted in any vehicle moving into or toward a block section having a defective or broken auxiliary trackway conductor circuit.

In a similar manner, safety relay SRB serves to give a restrictive signal in the event of failure of the motor alternator equipment. Each safety relay SR receives its current from the motor alternator in its block section and upon any failure of the motor alternator, relay SR opens breaking the circuit for the track current in next rearward main block section at point of contact 56.

By providing such relays provision is made for adequately safe-guarding against any failure of the equipment for upon such failure a more restricted condition is indicated than actually exists.

The particular type of cab signal equipment is not important so long as it is designed to translate the current in the track rails and auxiliary trackway conductor circuits into proper signals and/or controls. The reed relay type equipment is particularly well adapted for use with this invention.

By the terms "control" and "train control" as used in the specification and the claims I mean to include signals which indicate to the vehicle operator the proper control to be effected as well as direct mechanical or electrical control as in the device described above where the brakes of the vehicle are controlled. Likewise by the term "different current" as used herein in distinguishing the auxiliary trackway conductor and track currents, I intend to include alternating currents of different frequencies, alternating and direct current, alternating and pulsating direct current, and the like.

While I have illustrated and described certain preferred embodiments of my invention, the same is not limited to those described and illustrated but all other embodiments within the scope of the following claims:

I claim:

1. A trackway system for train control in tracks divided into block sections comprising means for impressing train control periodically varying current of one frequency upon the track rails in each block section only when the next advance block section is clear, an auxiliary trackway conductor disposed within a portion at least of each block section, and means for impressing train control periodically varying current of a second frequency upon the conductor in said block section only when the next or second advance block section is not clear, said currents of different characteristics flowing in said track rails and conductor respectively, either simultaneously or in one or the other depending upon advance traffic conditions.

2. A trackway system for train control in tracks divided into block sections comprising means for impressing train control periodically varying current of one frequency upon the track rails of each block section only when the next advance block section is clear, an auxiliary trackway conductor disposed within a portion at least of each block section, means for impressing train control periodically varying current of another frequency upon said auxiliary conductor when said next advance block section is not clear, and means for impressing said currents of different frequencies onto said track rails and conductor respectively, simultaneously when the said next advance block section is clear but the second advance block section is not clear.

3. A trackway system for train control in tracks divided into blocks each including a main and an intermediate section comprising means for impressing train control periodically varying current of one frequency upon the track rails in a section only when the next advance section is clear, an auxiliary trackway conductor in the intermediate section and a similar conductor in the exit end at least of the main section, means for impressing train control periodically varying current of a second frequency upon the conductor in the next rearward main or intermediate section when the adjacent advance section is not clear, and means for impressing said currents of different frequencies onto said rails and conductor respectively, in a rearward main or intermediate block section when the adjacent advance section is clear but the second advance section is not clear.
4. A trackway system for train control in tracks divided into block sections comprising means for impressing train control periodically varying current of one frequency upon the track rails of each block section when the next advance block section is clear, an auxiliary trackway conductor disposed within a portion at least of each block section, means for impressing train control periodically varying current of another frequency upon said auxiliary trackway conductor when said next or second advance block section is not clear, currents of different frequencies flowing in said track rails and conductor respectively, simultaneously or in one or the other depending upon advance traffic conditions, a train carried pick-up transformer for receiving said currents, and train carried means responsive to said train control currents for initiating signals indicating traffic conditions.
5. A trackway system for train control in tracks divided into block sections comprising means for impressing train control periodically varying current of one frequency upon the track rails of a block section when the next advance block section is clear, an auxiliary trackway conductor disposed within a portion at least of each block section, means for impressing train control periodically varying current of another frequency upon said auxiliary trackway conductor when said next or second advance block section is not clear, currents of different frequencies flowing in said track rails and conductor respectively, simultaneously or in one or the other depending upon advance traffic conditions, a train carried pick-up transformer for receiving said currents, train carried means responsive to said train control currents for initiating signals indicating traffic conditions, and a train carried receiver including means for translating said track current into one signal indication, means for translating said auxiliary trackway conductor current into a second signal indication, and means operative upon the failure of said track current for initiating a third signal.
6. A trackway system for train control in tracks divided into electrically insulated main and overlap block sections comprising means for impressing train control periodically varying current of one frequency upon the track rails in the main and overlap block sections in accordance with advance traffic conditions, auxiliary trackway conductors disposed within said intermediate block sections and the exit end at least of said main block sections, means for impressing train control periodically varying current of a second frequency upon the auxiliary conductors

in the main and overlap block sections in accordance with advance traffic conditions, a track relay responsive to the flow of said train control current in said main block section and effective for controlling the supply of train control current to the track rails in the next rearward intermediate block section, a track check relay responsive to the flow of said train control current in said intermediate block section and effective for controlling the supply of train control current to the track rails in the next rearward main block section, and a circuit controlled by said track relay for supplying energizing current to said track check relay when the track relay in the next advance main block section is deenergized.

7. A trackway system for train control in tracks divided into electrically insulated main and overlap block sections comprising means for impressing train control periodically varying current of one frequency upon the track rails in the main and overlap block sections in accordance with advance traffic conditions, auxiliary trackway conductors disposed within said intermediate block sections and the exit end at least of said main block sections, means for impressing train control periodically varying current of a second frequency upon the auxiliary conductors in the main and overlap block sections in accordance with advance traffic conditions, a track relay responsive to the flow of said train control current in said main block section and effective for controlling the supply of train control current to the track rails in the next rearward intermediate block section, a track check relay responsive to the flow of said train control current in said intermediate block section and effective for controlling the supply of train control current to the track rails in the next rearward main block section, a source of high voltage current and a resistor and a circuit controlled by said track relay for supplying current from said source through said resistor for energizing said track check relay when the track relay in the next advance main block section is deenergized.

8. A trackway system for train control in tracks divided into block sections comprising means for impressing train control periodically varying current of one frequency upon the track rails in one block section, an auxiliary trackway conductor disposed within said block section, an alternator for supplying train control periodically varying current of a different frequency to the conductor in said block section, either simultaneous with or separate from the supply of said track current, and means for controlling the supply of either frequency current to their respective rails or conductors, including a track current responsive relay in an advance block section controlling the supply of track current and conductor current to rearward block sections to provide conductor current only in the first rearward block section and track and conductor current simultaneously in the second rearward block section when said advance block section is not clear.

9. In a trackway system for train control in tracks divided into main and intermediate block sections, auxiliary trackway conductors in said sections connected together by a choke coil for the passage of direct current therethrough, a circuit for supplying alternating current to said trackway conductors, a direct current relay for initiating a restrictive control in a rearward block

section upon deenergization of said control relay through failure of said auxiliary trackway conductor circuit, a circuit for the supply of direct current for energizing said control relay, said circuit being completed through said conductors and choke coil, and a blocking condenser in the alternating current supply circuit for blocking the entrance of direct current into the alternator.

10. In a trackway system for train control in tracks divided into main and intermediate block sections, auxiliary trackway conductors in said sections connected together by a choke coil for the passage of direct current therethrough, a circuit for the supply of train control current in a rearward block section, a direct current relay in said circuit for initiating a restrictive control in said rearward block section upon deenergization of said control relay through failure of said auxiliary trackway conductor circuit, a circuit for the supply of direct current for energizing said control relay, said circuit being completed through said conductors and choke coil, and a blocking condenser in the alternating current supply circuit for blocking the entrance of direct current into the alternator.

11. A trackway system for train control in tracks divided into electrically insulated main and overlap block sections comprising a circuit for supplying train control periodically varying current of one frequency to the track rails in the main and intermediate block sections, a track relay responsive to the current in the main block section and controlling the supply of train control current to the track rails in the next rearward intermediate block section, a track check relay responsive to the current in the intermediate block section and controlling the supply of train control current to the track rails in the next rearward main block section, auxiliary trackway conductors disposed within the main and intermediate block sections, an alternator for supplying current of a second frequency to the trackway conductors, a circuit controlled by said track relay and said track check relay to initiate said alternator upon deenergization of either of said relays, a circuit permanently connecting the auxiliary trackway conductor in the main block section to said alternator, and an independent circuit controlled by the track relay in the next advance main section connecting the auxiliary trackway conductor in the intermediate block section to the alternator to provide for the flow of current only in the auxiliary conductor when the next advance block section is not clear, in the rails and conductor respectively, simultaneously when the next advance block section is clear but the second advance block section is not clear, and only in the rails when at least two sections in advance are clear.

12. In a trackway system for train control in tracks divided into sections, an auxiliary trackway conductor, means for supplying current of one frequency to the track rails, an alternator for supplying current of a different frequency to the conductor, a safety relay for controlling the supply of current to the track rails in a rearward block section to initiate a restrictive control in said rearward block section in the event of failure of said alternator, and a circuit for supplying current from said alternator to energize said safety relay only so long as said alternator is in operation.

13. In a trackway system for train control in tracks divided into sections, an auxiliary track-

way conductor, means for supplying current of one frequency to the track rails, an alternator for supplying current of a different frequency to the conductor, a track relay connected to the rails and responsive to said current of one frequency, a safety relay for controlling the supply of current to the track relay in a rearward block section to initiate a restrictive control through said track relay in the event of failure of said alternator, and a circuit for supplying current from said alternator to energize said safety relay only so long as said alternator is in operation.

14. In a trackway system for train control in tracks divided into sections, an auxiliary trackway conductor, means for supplying current of one frequency to the track rails, means for sup-

plying current of a different frequency to the conductor, and a safety relay energized by said current of different frequency for controlling the operation of a relay in a rearward block section to initiate a restrictive control in said rearward block section in the event of failure of said means for supplying current of a different frequency to said conductor.

15. A trackway system in accordance with claim 3 in which the means for impressing train control periodically varying current of a second frequency includes an alternator for supplying current of a frequency different from the current supplied to the track rails.

MAX THEODORE WINTSCH.
